CLAIM

The ornamental design for a projectile, as shown and described.

DESCRIPTION

FIG. 1 is a perspective view from a first side of a projectile according to one embodiment of the present invention; FIG. 2 is a perspective view from a second side of the projectile according to FIG. 1;

FIG. 3 is a rear view of the projectile according to FIG. 1; FIG. 4 is a front view of the projectile according to FIG. 1; FIG. 5 is a top view of the projectile according to FIG. 1; FIG. 6 is a bottom view of the projectile according to FIG. 1;

FIG. 7 is a left side view of the projectile according to FIG. 1;

FIG. 8 is a right side view of the projectile according to FIG. 1;

FIG. 9 is a perspective view from a first side of a projectile according to a second embodiment of the present invention; FIG. 10 is a perspective view from a second side of the projectile according to FIG. 9;

FIG. 11 is a rear view of the projectile according to FIG. 9; FIG. 12 is a front view of the projectile according to FIG. 9; FIG. 13 is a top view of the projectile according to FIG. 9;

FIG. 14 is a bottom view of the projectile according to FIG. 9;

FIG. 15 is a left side view of the projectile according to FIG. 9; and,

FIG. 16 is a right side view of the projectile according to FIG. 9.
